UNITED STATES PATENT OFFICE.

ASBURY LINCICOME, OF PERSHING, OKLAHOMA.

WASHING MACHINE.

Application filed October 7, 1922. Serial No. 593,149.

To all whom it may concern:

Be it known that I, ASBURY LINCICOME, a citizen of the United States, residing at Pershing, in the county of Osage and State of Oklahoma, have invented new and useful Improvements in Washing Machines, of which the following is a specification.

This invention relates to laundry apparatus, particularly to mechanical clothes washers, and has for its object the provision of a novel washing machine of the rotary type which will operate efficiently to cleanse clothes in a rapid and thorough manner and with the expenditure of the minimum labor.

An important object is the provision of a rotary tub of novel construction provided interiorly with means for preventing the clothes from knotting together or balling up in a compact mass which might interfere with the free passage of water therethrough.

Another object is the provision in a washing machine of this character of means for beating the clothes for the purpose of effectually loosening the dirt.

Still another object is the provision of a washing machine of this character in which the tub member may be formed entirely of metal and provided with peculiarly constructed ribs operating to loosen the dirt.

An additional object is the provision of a device of this character which will be simple and inexpensive in manufacture, easy to operate, efficient and durable in service and a general improvement in the art.

With the above and other objects and advantages in view the invention consists in the details of construction to be hereinafter more fully described and claimed and illustrated in the accompanying drawings, in which:

Figure 1 is a side elevation of the device.

Figure 2 is a top plan view,

Figure 3 is a vertical section,

Figure 4 is a vertical section taken at right angles to Figure 3,

Figure 5 is a plan view of a portion of the interior of the tub considering it as flattened out,

Figure 6 is a detail view through a modified form of tub showing the provision of beating means for the clothes,

Figure 7 is a detail plan view of the inside of a modified form of tub of all metal construction and

Figure 8 is a cross section therethrough.

Referring more particularly to the drawings the numeral 10 designates a supporting stand which may be constructed of angle iron or other suitable material and which includes legs 11 braced as shown at 12 and carrying a horizontal frame 13 provided at opposite sides with bearings 14 which receive shafts 15 carrying a tub 16. Secured upon one shaft is a gear 17 with which meshes a gear 18 on a shaft 19 journaled on the frame and provided with a crank handle 20 which may be turned to effect rotation of the tub. On the side opposite the gear is a fly wheel 21 secured to the other shaft 20 for the purpose of insuring a more uniform rotation of the tub. I also provide a small pulley 22 so that the device may be driven from any suitable source of power by means of belting instead of being manually operated. It is preferable to provide a sheet metal housing or casing 23 bolted onto the frame and which will enclose the gearing and protect the same.

The numeral 24 designates a supporting frame which is carried by the frame 10 and upon which may be mounted any ordinary or preferred wringer, not shown, which will be a great convenience as permitting the clothes to be wrung immediately after being taken from the tub. Located beneath the wringer is a chute or trough 25 which has its sides formed with slots 26 slidably and rotatably engaged upon a rod 27 and designed to catch water squeezed out of clothes by the wringer for the purpose of returning this water to the tub instead of allowing it to drop upon the floor. I also find it expedient to provide a pan 28 located beneath the tub and fastened to the frame 13 to form a trough for the purpose of catching all the water that might be spilt, the trough having a normally closed outlet 29 at its bottom so that the water can be drained off into a pail or the like.

The tub is cylindrical as above stated and may be formed either of wood or metal and is provided at a convenient point with a door 30 for the insertion and removal of clothes and for the pouring in of water or soap suds. Extending longitudinally of the tub in spaced relation to the inner periphery thereof are rods or bars 31. These rods prevent the clothes from sliding idly with respect to the tub during rotation thereof and therefore prevent the clothes from balling together or knotting up into a compact mass.

The tub may be provided with a drain cock, if desired, though the cover or door may be opened and the tub partly turned to empty the water into the pan 28 from which it may be readily drained. When the cover 30 is open and it is desired to operate the wringer, the chute 25 is turned and slid into the position shown in Figure 4, engaging the edge of the open part of the tub so that the water squeezed out of clothes by the wringer will be returned to the tub.

If preferred I may provide beating means as shown in Figure 6, this beating means consisting of lengths of chain 32 secured to the periphery of the tub and also to the rods or bars 33. These chains of course operate to beat or pound the clothes when the tub is rotated and thus operate to loosen the dirt so that it may be easily washed out.

20 In Figures 7 and 8 I have shown a modified tub structure in which the tub is formed preferably of sheet metal. This tub is likewise cylindrical in shape and is provided on its inner periphery with a plurality of 25 transverse ribs 34 which are formed of sheet metal bent into substantially V-shape and which have side flanges 35 soldered or brazed onto the tub. These ribs have their edges and both sides formed with a plurality of holes 36 for the free circulation 30 of water. The operation of this form is the same as that of the first described form, the ribs operating to rub the clothes in a manner similar to the rubbing action of an ordinary wash board.

From the foregoing description and a study of the drawings it will be apparent that I have thus provided a simply constructed and consequently inexpensive washing machine which is mechanically operated and which will remove dirt from clothes in a very rapid and efficient manner without

much labor and without causing any injury to or unusual wear upon the clothes. Owing to the simplicity of the construction and the fewness of the parts it is apparent that there is practically nothing to get out of order and that the device should thus have a long life and satisfactorily perform all of its functions.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. In a washing machine including a frame and a pan, a tub rotatably mounted within the frame and pan, and a plurality of lengths of chain secured at one end within the tub and acting to beat clothes disposed therein.

2. In a washing machine, a rotary tub adapted to contain clothes to be washed, a plurality of rods extending longitudinally of the tub at points spaced from its periphery, and a plurality of lengths of chain 70 carried by said rods and adapted to act as clothes beaters.

3. In a washing machine, a rotary tub adapted to contain clothes to be washed, a plurality of rods extending longitudinally 75 of the tub at points spaced from its periphery, and a plurality of lengths of chain carried by said rods and adapted to act as clothes beaters, and other chains connected with the inner periphery of the tub and likewise beating the clothes.

In testimony whereof I affix my signature.

ASBURY LINCICOME.
